UNITED STATES PATENT OFFICE.

FRANK SHUMAN, OF PHILADELPHIA, PENNSYLVANIA.

METHOD OF MAKING COMPOSITE PILES.

1,156,186.

Specification of Letters Patent.

Patented Oct. 12, 1915.

Application filed March 7, 1906. Serial No. 304,677.

To all whom it may concern:

Be it known that I, FRANK SHUMAN, a citizen of the United States, residing in Philadelphia, Pennsylvania, have invented 5 certain Improvements in Methods of Making Composite Piles, of which the following is a specification.

The object of my invention is to improve the method of making composite wood and 10 concrete piles of that class in which the base is of wood and the superstructure is of concrete.

In the accompanying drawings, Figure 1, is a view showing part of a wooden pile and 15 part of the superposed structure whereby said pile is driven below the surface of the ground, the full lines showing the relation of the wooden pile to the surface of the ground before such driving operation, and 20 the dotted lines showing the relation of the pile to the surface of the ground after the driving operation has been completed; Fig. 2, is a view similar to Fig. 1, but illustrating the position of the parts after the 25 mass of concrete has been introduced and is about to be forced into the opening in the ground formed by the driving of the wooden pile below the surface.

Referring in the first instance to Figs. 30 1 and 2, of the drawing, 1 represents the wooden pile, which is of a length appropriate for this member of the composite pile. I first drive this wooden pile into the ground until its top approaches the surface of the 35 ground, as shown by full lines in Fig. 1, if the composite pile is to be formed in solid ground, or until the top of the wooden pile approaches the surface of the water, if the pile is being driven in submerged ground. 40 I then provide the wooden pile with a central dowel pin 2, which projects some distance above the top of said wooden pile, and upon the latter are then mounted a driving form, and, if the pile is to be driven 45 under water a surrounding tubular form intended to form a watertight joint with the top of the wooden pile. The latter form may also be employed if the pile is being driven in wet or marshy ground, or 50 under any circumstances, where it is desirable to prevent water or unstable soil from filling the opening formed in the ground by driving the wooden pile below the surface.

55 The driving form consists of a tube 3 pivoted at its upper end by means of a trans-

verse pin 4 to the driving head 5, which is suitably guided in the leads of the pile driver and is preferably provided with a wooden plug 6 for receiving the blows of 60 the hammer.

The lower end of the tubular driving form 3 is provided with a cap 7 secured thereto by means of a transverse bolt or rivet 8, this cap providing an extended bearing for the driving form upon the top of the wooden pile and having a central opening 9, preferably tapered, so that said cap will, by engagement with the dowel pin 2, be guided into a central position on 65 the top of the wooden pile as it is lowered onto the same. In order to prevent access to the interior of the tubular driving form 3 through the opening 9, said form has an internal tube 10 for the reception of the 70 dowel pin 2, this tube being closed at its inner end by means of a cap 11 suitably secured to it to effect a tight closure of the 75 upper end of the tube.

The waterproofing form 12 surrounds the 80 driving form 3, and consists of a relatively light sheet metal tube of somewhat greater length than the distance from the under face of the driving head 5 to the under face of the cap 7 of the driving form, whereby, when 85 the two forms are first placed upon the top of the wooden pile, the cap 7 of the driving form will be supported some little distance above the top of the wooden pile, and the first blow or succession of blows delivered by the 90 piledriver will be devoted to driving the lower edge of the tube 12 into the top of the wooden pile 1, thus forming a perfectly watertight joint between the two by the time the cap 7 of the driving form contacts with the top of 95 the wooden pile, as shown in Fig. 1, the force of the subsequent blows of the pile driver being then transmitted to the wooden pile through the medium of the driving form 3.

The confinement of the upper portion of 100 the pile by the form 12, also serves to prevent the splitting or splintering of said confined portion of the pile under the blows of the hammer transmitted through the medium of the driving form 3.

When the wooden pile has been driven to the proper depth the driving form 3 is withdrawn, leaving the form 12 in position on the pile. The said form 12 is then filled to the desired extent with concrete, and the 110 driving form is lowered onto the top of the concrete mass in order to ram or pack the

concrete in the tube 12, either by the weight of the driving form or by blows of the pile driver delivered thereupon. If the concrete member of the pile is to be sheathed, this 5 may complete the operation, but if said concrete member is to be produced directly in the ground, the form 12 can be withdrawn before or during the ramming operation. By preference it is gradually withdrawn 10 while the ramming of the concrete is being effected, the concrete escaping below the lower edge of the form 12 and filling the opening which has been formed in the ground by the driving of the pile 1 below the 15 surface of the same. (See Fig. 2.) A rammer other than the driving form may be used if desired.

My invention provides a convenient method of forming a composite pile in which 20 the concrete member is tapered or flared outwardly from top to bottom.

The driving form may be a tube properly flared or tapered, or it may be a solid or collapsible form.

25 During the introduction of the concrete into the waterproofing form, any desired metallic reinforce may be embedded therein in order to increase the strength of the concrete member of the pile, one such form of 30 metallic reinforce being shown in Fig. 2. Said reinforce may be introduced as a whole before the introduction of the concrete, or it may be built up as the concrete gradually

fills the form, for instance the vertical rods 20 may be introduced at first, and, as the 35 concrete is filled in, the bracing rings 21 may be successively slipped down over the rods.

I claim:

The mode herein described of forming a 40 composite wooden and concrete pile; said mode consisting in first driving a wooden pile alone into the ground to the extent of its length; second, mounting the driving form upon the end of the wooden pile and 45 centering it thereon; placing a casing around the driving form and resting it upon the exposed end of the wooden pile; driving the casing into the end of the wooden pile for a given distance to form a water tight joint; 50 then driving the said wooden pile to a point below the surface of the ground through the medium of the superimposed driving form, the casing being driven simultaneously with the pile; then withdrawing the driving form, leaving the casing in the ground; and 55 then filling the casing with concrete to complete the pile structure.

In testimony whereroof, I have signed my name to this specification, in the presence of 60 two subscribing witnesses.

FRANK SHUMAN.
